US00D866453S

(12) **United States Design Patent** (10) Patent No.: **US D866,453 S**
van't Hul et al. (45) Date of Patent: ** Nov. 12, 2019

(54) **TIRE**

(71) Applicant: **APOLLO TYRES GLOBAL R&D B.V.**, Enschede (NL)

(72) Inventors: **Wim van't Hul**, Deventer (NL); **Rob Eshuis**, Nijverdal (NL)

(**) Term: **15 Years**

(21) Appl. No.: **35/505,138**

(22) Filed: **Jun. 1, 2018**

(80) **Hague Agreement Data**

Int. Filing Date: **Jun. 1, 2018**

Int. Reg. No.: **DM/101492**

Int. Reg. Date: **Jun. 1, 2018**

Int. Reg. Pub. Date: **Jun. 15, 2018**

(30) **Foreign Application Priority Data**

Dec. 1, 2017 (EM) 004529956

(51) **LOC (12) Cl.** **12-15**

(52) **U.S. Cl.**

USPC **D12/563**

(58) **Field of Classification Search**

USPC D12/533-567

CPC B60C 2011/0358; B60C 2011/0374; B60C 11/0302
